UNITED STATES PATENT OFFICE.

WALTER SCOTT, OF PLAINFIELD, NEW JERSEY.

PRINTING AND FOLDING MACHINE.

No. 810,225.

Specification of Letters Patent.

Patented Jan. 16, 1906.

Application filed February 19, 1897. Serial No. 624,266.

To all whom it may concern:

Be it known that I, WALTER SCOTT, a citizen of the United States, and a resident of Plainfield, in the county of Union and State 5 of New Jersey, have invented certain new and useful Improvements in Printing and Folding Machines, of which the following is a specification.

This invention relates to machines for 10 printing and folding one or more webs and delivering the products formed from the same.

One object of the invention is to fold the successive cuts from the web or webs without 15 collecting them or by a simple adjustment to collect and fold the cuts.

Other objects will appear hereinafter.

To these ends the invention includes features of construction and combination of devices hereinafter described, and more particularly pointed out in the appended claims.

The preferred form of the invention is illustrated in the accompanying drawings, forming part of this specification, in which—

25 Figure 1 is a diagrammatic side elevation showing five web-presses A B C D E, arranged one over another, with four rolls of paper, a folder, and parts of the driving mechanism. Fig. 1^a is an enlarged view of parts shown in Fig. 1. Fig. 2 is an end view, on an enlarged scale, of the cutting, collecting, and folding mechanisms and a delivery. Fig. 3 is a plan view of part of the mechanisms shown in Fig. 2. Fig. 4 is a diagrammatic side elevation, 30 on an enlarged scale, of parts of the presses C D E shown in Fig. 1 and showing various paths for the webs. Fig. 5 is a view of the parts shown in Fig. 4 for changing the direction of rotation of the first impression-cylinder of the press D. Fig. 5^a is a plan view of mechanism for changing the direction of rotation of said first impression-cylinder. Fig. 45 6 is an elevation from the side of the machine, showing parts of a driving mechanism, a belt-shifter, and a brake mechanism. Fig. 7 is an elevation, partly in section, on the plane indicated in Fig. 6 by the line 5 5 of the devices shown in Fig. 6. Fig. 7^a is a view of speed-changing gearing intermediate the 50 drive-shaft and the presses. Fig. 8 is an end view, and Fig. 9 is a side view, of a modification of the collecting and folding mechanisms shown in Figs. 2 and 3. Fig. 10 and Fig. 11 are detail views.

55 The same reference character will be used

to designate the same part in the various figures of the drawings.

A B C D E indicate five web-perfeting presses of the well-known rotary type, the plate-cylinders *t*, impression-cylinders *i* *i*² *i*³ *i*⁴ *i*⁵, and inking apparatus of which may, with the modifications to be described, be of any usual or desired character. The presses A B C are respectively supplied with webs *w* *w*² *w*³ from rolls *W* *W*² *W*³, placed one above another, as shown, the webs being led over suitable guides, as rolls *a* *b*, to and between the first plate and impression cylinders of the presses A, B, and C. From the second impression-cylinders of these presses these webs are led around suitable guides, as rolls *d* *e* *f* *g* *h* *k* *l*, to and over the triangle or longitudinal former, where the associated webs receive a longitudinal fold.

Instead of conducting the web *w*³ through the press C direct the same may be led upwardly from between the first and second impression-cylinders of the said press (thus receiving a first or preliminary impression on one side in the press C) to and between the first plate and impression cylinders of the press D (and the press E, if so desired) and down between the second plate and impression cylinders of the press D and the press E, if it has also been led up between the first plate and impression cylinders of said press E, to and between the second plate and impression cylinders of the press C, and thence to the folder, as above described. In this way one side of the web *w*³ may receive as many as five successive impressions, each in a different color. In order to allow of the rotation of the cylinders of the presses D and E in the proper directions, the impression-cylinders of each are slightly separated from each other. The first impression-cylinder of the press E always rotates in the same direction as the second impression-cylinder of that press. The first impression-cylinder of the press D is arranged to be driven in either direction, according as the web is to be led up or down between the first plate and impression cylinders thereof. In case the web *w*³ is led through the presses C D E in the order named for the first impressions the first plate and impression cylinders and coating inking devices of the presses D E are revolved in a direction contrary to that in which the like parts of the presses A B C are revolved. In case the web *w*⁴ is to receive a number of im-

pressions on one side, as in multicolor printing, it is run through the press D between cylinders t^2 and is led thence through the press E between cylinders t^4 and t^5 , and is thence returned to press D between cylinders t^3 and t . In this case the cylinders of the press D rotate, as do the cylinders of the presses A B C, while the impression-cylinders of the press E rotate in the same direction as the cylinder t^3 of the press D. From the press D the web w^4 is led around guides, as rolls $e h g$, to the rollers $k l$ and the folder F. The details of the mechanism for securing the required motions of the various cylinders will be set forth hereinafter. After passing the rolls $k l$ the webs are given a longitudinal fold by the folder F and the coacting outside guides or rolls n . The rollers n are provided with collars o thereon which are of somewhat greater diameter than the rolls on which they are placed. The collars act only on the margins of the webs, and at least one of the collars o is adjustable on its roll n or on the shaft thereof, as by a set-screw or bolt o^x , in order that it may be adjusted to coact with the margins of webs of different widths. The adjustable collar is at the end of the roll n which is away from the point of the former F, and its coacting non-adjustable collar is merely long enough to coact therewith in all positions of the adjustable collar, or one collar on each roll n may be adjustable, as above set forth.

Mechanism whereby the web w^3 may be taken through the presses D E will now be described. After passing about the first impression-cylinder of the press C this web is led about a register-roll m , then up between the impression-cylinders i^2 i^4 and their coacting plate-cylinders of the presses D E to the second impression-cylinders of these presses, thence downwardly between the second impression and plate cylinders of the press C, and thence to the folder F. The cylinder i^2 and its coacting plate-cylinder t are caused to rotate in the required directions as follows: The second impression cylinders of all the presses are driven from the vertical shaft 51 by miter-gears 52 53, and the first impression-cylinders of the presses A B C are driven direct from second impression-cylinders of these presses; but in the case of the press D the first impression-cylinder thereof is driven from the first impression-cylinder of the press C by means of pinions 48 49 50, when the web w^3 is run through the press D or presses D and E as well as through the press C. In case the web from the press C is not to be run through the press D and the web w^4 is to be used the impression-cylinder i^2 of the press D is driven from the second impression-cylinder of the press D by the pinions 46 47, a suitable register-roll c being employed between the presses D and E in case the web w^4 is also run through the press E. Whenever the web

from the press C is run through the press D, one of the pinions 46 47, as pinion 47, is unkeyed from its shaft or is moved along the same until it is out of mesh with the other pinion, as pinion 46, and whenever the web from the press C is not run through the press D and the web w^4 is used on the press D the pinions 49 50 are disengaged by shifting one of them, as pinion 50, along its shaft or stud until it is out of mesh with the other, as pinion 49, or it is simply unkeyed from its shaft. By "unkeying" is meant that the gears are so loosened from their shafts as that the two can rotate independently of each other. The second impression-cylinder of the press E drives the first impression-cylinder thereof through an intermediate gear 54.

In presses D E, I show distributing-rolls 55 underneath the distributing-cylinders 56 for use when the web w^3 is run through the press D. In presses A B C D are shown distributing-rolls 255 over the distributing-cylinders for the first printing-cylinders, such rolls coacting with their corresponding distributing-cylinders. Also in press D are shown an impression-cylinder i^2 , arranged to be rotated in either direction, as elsewhere herein set forth; a plate-cylinder t , coacting with cylinder i^2 and driven therefrom; a distributing-cylinder 56 and form-rolls 155 between the cylinders 56 and t ; distributing-rolls 55 below the cylinder 56 and like rolls 255 above such cylinder 56; a roll 156 for coaction with a ductor-roll 157 and one of the rolls 255; an ink-fountain 158, and a fountain-roll 159. From this construction and arrangement it results that the forms on the cylinder t are uniformly and properly inked, whichever may be the direction of rotation of said cylinder.

It is understood that the inking apparatus of the press D is rotated each set or side from its own impression and plate cylinders, thus following the motions of the latter.

From the foregoing it is seen that one object of the invention is to run one or two webs through the same two (or more) presses. Another object of the invention is to stop a plurality of presses without causing undue strain upon the gearing of the presses or machine. Means for securing the object last named will next be described.

In Figs. 6 and 7 I show a belt-shifter or power-controller and a brake mechanism on impression-cylinders of the presses as being connected to and operated by a lever at one side of the machine. The connecting mechanism is conveniently made in the form of a lever, as 57 or 58, or arm of a rock-shaft 59 at one side of the machine and a second rock-shaft 60, parallel with shaft 59, said shaft 60 being provided with three arms 62 63 70; a link or pitman 61, which is pivotally connected to the lever 57 and arm 62; a rod 79, which is pivotally connected with the arm 63 and with the shifter 64 and which is suitably

guided in the framework, as at 80; a lever 72, pivoted at 73 to the framework and connected with arm 70 by a link 71, and a vertical rod 74, which is connected with each brake mechanism on the various presses. The brake mechanism shown in the drawings comprises a brake-wheel 76, which is connected with one of the cylinders of a press, or there is one such wheel for each press, as by being formed on the boss of a miter-gear 53, and the brake-shoes or levers 75, which are pivoted to the framework at 77 and to the vertical rod 74 at a point on the opposite side of the boss from the pivots 77. In order to apply the brakes as the power is thrown off, the transverse driving-shaft 68 is provided with a loose pulley 65, a slow-speed pulley 66, and a fast pulley 67 for the higher speeds, the slow-speed pulley being the intermediate. The pulley 67 is fast upon the shaft 68, while pulley 66 is fast to a sleeve or hub of a pinion 65^a, which is loose on the shaft, and pulley 65 is loose on said sleeve or hub. The pinion 65^a meshes with a larger gear 65^b, which is mounted on a counter-shaft, and a pinion 65^b, smaller than gear 65^a, is rigidly connected with gear 65^b. A gear 65^c larger than pinion 65^b, is fast to the shaft 68 and meshes with pinion 65^b. When the belt is on the pulley 67, the shaft 68 is driven at a maximum speed. When the belt is on the pulley 66, the shaft 68 is driven through the train of gearing just described and at a reduced rate of speed, the speed of the belt remaining unchanged, and when the belt is on pulley 65 no power is transmitted to the shaft 68. The arrangement of the parts is such that whenever the belt is shifted onto the loose pulley the brakes are applied and that the brakes are taken off whenever the belt is shifted off the loose pulley. The attendants, always to be found at the ends of the presses, can throw the machine into and out of operation at will by the described mechanism, the levers 57 58 being within convenient reach at the ends of the machine. There are great advantages in having the slow-speed pulley intermediate the loose and the fast pulleys, for in starting up the machine from rest the belt is first run onto the slow-speed pulley and the presses given a slow start without shock or strain on the gearing and is afterward run onto the tight or fast pulley. In stopping the machine shock and undue strain are avoided in that the belt is run off the tight pulley onto the slow-speed pulley and then onto the loose pulley. In connection with the brake mechanism described there is a minimum of danger of breaking the gearing in stopping the machine, for the brakes are applied to all the presses at the time the belt is run onto the loose pulley.

The invention also includes a rotating sheet-carrier provided with a number of folding or creasing blades, in combination with a

rotating carrier to which the sheets are transferred and mechanism for preventing the transfer except at stated times, thus allowing of the collecting of sheets before the folding is done. The invention also includes the combination, of a rotating sheet-carrier provided with a number of movable folding or creasing blades, with mechanism for protruding said blades in alternation or alternately. The invention also includes a rotating sheet-carrier provided with a number of movable folding or creasing blades, in combination with mechanism for protruding the blades in stated order and a disconnectible part whereby the mechanism may be adjusted to fold the cuts singly or to collect and fold them, and other combinations are also included in the invention, as will appear more fully hereinafter. The particular embodiment of this part of my invention which is shown in the drawings includes a rotating cylinder provided with three creasing or folding blades movable in and out relatively thereto, as radially, three sets of sheet-retainers, as grippers, two movable cams for protruding the blades alternately or otherwise, and mechanism for moving the cams into and out of the positions in which they protrude the blades. By preference these cams have a motion of rotation and are driven at a speed such that they overtake or are overtaken by the creasers in succession as the creasers pass the place where the sheets are folded off the carrier—that is, the cams gain or lose one-third of a revolution in the case where there are three folding-blades on the carrier in the intervals between successive foldings-off. Thus the cams gain when folding off two, five, eight, &c., sheets and lose when folding off four, seven, ten, &c., sheets; but it is not possible with the mechanism shown in the drawings to collect and fold sheets equal in number to the folding-blades or to any integral multiple thereof.

Below the rolls *n* above described are the usual cutting-cylinders, as *p q*, whose cutting-blades may sever the sheets from the web or webs or may merely perforate the webs and the sheets be torn from the webs in a well-known manner. The heads or leading edges of the webs or sheets are guided down to the sheet-retainers, as grippers, of a cylinder *G* by fixed guides *r* and tapes *s*, the latter running on pulleys or rolls *u*. One set of these pulleys or rolls *u* may be adjustable, and so act as tension-rolls, as by being supported from or by the shaft *v*. The guides *r* are supported by a shaft *r'* in the framework of the machine.

The cylinder *G* shown in the drawings comprises a number of rings or disks 13, which are supported from the shaft 11 by arms 12, the shaft 11 being suitably journaled in the framework *z* of the machine. The cylinder *G* is provided with longitudinally-extending

radial grooves for the reception of three folding-blades $x y z$, which are held and guided thereby. The cylinder G is also provided with three sets of grippers 16 17 18, which lie in three longitudinally-extending grooves in the cylinder, said grippers being borne by shafts 16^a 17^a 18^a, which are suitably journaled in the end or other of the rings or disks 13. The said sets of grippers coact with the leading ends of the sheet-receiving surfaces of the carrier G to retain the leading ends of the web or webs or the sheets thereagainst. The usual springs for keeping the grippers closed may be employed, but are not shown. The cylinder G in the form shown in Figs. 2, 3, 8, and 9 is driven from a side shaft 27 by a train of gears P T S O, the last being fast to the shaft 11 of the cylinder. The gear P is fast on a shaft Q, which is journaled in the framework X, and is driven from the side shaft 27 by the gears S T, the former of which is fast on a shaft 26. At each end of the cylinder G are pinions M, which are loose on the shaft 11, so as to be rotatable independently thereof. The shaft Q is provided with pinions R, which mesh with the gears M aforesaid. The relative sizes of the gears R O M P are such that the gears M make three revolutions to two of the gear O, and therefore of the cylinder G. The gears M are provided with grooved cams N, which are concentric with the gears M, except at their working parts N'. It results from the described sizes of the gears R O M P that the parts N' of the cams N pass the point where the folding-off of the sheets occurs with every other one of the folding-blades and protrude the same, since these blades $x y z$ are provided with antifriction-rolls 28 29 30, which engage with the said grooved cams N—that is, the rollers or bowls 28 29 30 revolve about the same axis as cams N, though in different times, and control the motion of the blades $x y z$ radially of the carrier, since these bowls are continuously in engagement with the cams N.

The carrier G coacts with a cylinder H to fold the cuts from the webs. The cylinders G H have the same surface speed as the cylinders of the presses, and the grippers of the cylinder G push out the tails of the sheets or cuts as they are opened by a cam 21 to take the heads of the web or webs or sheets, or the cylinders G H may be run at a slightly greater surface speed than the cylinders of the presses, and so bring about the separation of the tails and heads of the successive cuts. The grippers 16 17 18 are opened each time they pass by the fixed cam 21 to take the heads of the cuts and are opened each set during alternate revolutions of the carrier G by a movable cam 22, which is moved into and out of the path of the antifriction-rollers 19 20, with which crank-arms at one end of the shafts 16^a 17^a 18^a are provided. The cam 22 is pivoted at 23 to the frame X and is moved into

and out of the path of said rollers 19 20 by a rod 24 and an eccentric 25 on the shaft 26, the rod 24 being connected to the eccentric by a strap, as us $\frac{1}{4}$. The cylinder H is provided with two longitudinal bars 14 15, in front of which are longitudinal grooves in the disks forming the cylinder H, and with two sets of grippers 2 5, which are respectively on shafts 3 6. The shafts 3 6 are suitably journaled in the cylinder H and are kept in position to close the grippers 2 5 by springs (not shown) in the usual manner. The grippers 2 5 coact with the bars 14 15 to grip sheets. The shafts 3 6 are provided with antifriction-rollers 4 7, with which cams 8 9, 80 fixed to the framework, coact to open the grippers 2 5 at the proper times, as will appear hereinafter.

Adjacent to the cylinder H is a delivery-cylinder K, which is or may be formed of 85 disks fastened to a shaft 31. The cylinder K is provided with a shaft 33, journaled therein and carrying grippers 34 for receiving sheets from the grippers of the cylinder H. Two suitably-placed fixed cams 36 37 coact with 90 the roller on the crank-arm of the shaft 33 to open the grippers 34 against the force of a closing-spring. (Not shown.) The fixed guides 38 coact with the cylinder K to retain the sheets in place thereagainst. The sheets 95 are delivered to guides 39 by the cylinder K and are pushed from the guides by the vibratory arms 40 as the copies reach a stop 41 and onto traveling tapes 42, which are moved by pulleys or rollers 43. This delivery is fully 100 described in my Letters Patent of the United States granted the 24th day of November, 1896, and bearing No. 571,982.

The shaft 10 of the cylinder H is provided with a gear U fast thereto, which meshes with the gear O, and the shaft 31 of the cylinder K is provided with a gear V fast thereto, which meshes with the gear U, so that the cylinders G H K have equal surface speeds.

The operation of the folding devices thus far described will now be set forth, reference being had to my Letters Patent of the United States dated the 1st day of December, 1896, and bearing No. 572,280, in which Fig. 7 shows the order of folding the cuts when collecting two sheets, when the cams N make three revolutions to two revolutions of the carrier G. The positions of the parts in Figs. 2 and 3 hereof are similar as far as the similarity can extend to the positions of parts in Figs. 2, 3, and 4 of said last-named Letters Patent, there being a cut passing from the carrier G to the cylinder H, the grippers 17 being open and the blade x being protruded, as shown. As the grippers 16 approach the point of the guides $r r^2$ they are opened by the cam 21 and close in time to take the ends of the webs as the latter are fed down toward the cylinders G H, thus causing one sheet to be laid upon the succeeding sheet-receiving 130

surface of the carrier G. The grippers 16 next pass the cam 22 without being opened thereby, as that cam at this time is removed from the path of the arm of shaft 16^a, by 5 which the shaft and grippers 16 are operated. The grippers 18 are next operated to take the ends of the webs coming down from the cutting-cylinders, thus causing the succeeding sheet to be laid upon another sheet-receiving 10 surface of the carrier G, and are opened by the cam 22 as they pass it, for it has been moved by this time into the path of the roller on the crank-arm of the shaft 18^a, while the blade y is protruded by the working parts N' 15 of the cams N to fold the cuts off onto the cylinder H. The grippers 17 are next operated to take the ends of the webs coming from the cutting-cylinders, thus causing the next succeeding sheet to be laid upon the next 20 succeeding sheet-receiving surface of the carrier G and these grippers are not opened by the cam 22 as they pass the same, as it is at this time withdrawn from the path of the gripper-shaft arm. The grippers 16 next take 25 the ends of the webs and are then opened by the cam 22, while the blade z is protruded by the cams N, whose parts N' have overtaken the rollers 30 as the latter approach the cylinder H. Next the grippers 18 seize the ends 30 of the webs and carry the cut around the cylinder G, the cam 22 being in its non-working position as these grippers pass by it. Then the grippers 17 take the ends of the webs and are opened by the cam 22, while the parts N' of the 35 cams N have overtaken the rollers 29, and so protrude the blade z, as shown in the drawings. It is observed that during the above-described operation the blades x y z are protruded each during non-successive revolutions of the carrier G. The described cycle of operations is 40 repeated during the further operation of the machine. As the cuts are folded off the cylinder G onto the cylinder H they are taken by the grippers 2 5 thereof and are transferred to the grippers of the cylinder K and 45 thence are passed to the delivery. In case the cuts are not to be collected but are to be folded separately the gears M, and with them the cams N, are locked against motion, as by 50 the pins 44, which are inserted in the holes 45 in the gears through suitable holes in the framework of the machine and the gear O, the working parts N' of each cam N being opposite the cylinder H in position to protrude 55 the blades x y z as these pass the cylinder H. At the same time the pinions R are moved longitudinally of their shaft out of mesh with the pinions M or the gears O, the working parts N' of each cam N being unkeyed from their shaft, so as not to be turned there- 60 by. Also the cam 22 is fixed in position to open the grippers 16 17 18 as these pass by each time. This may be done conveniently by unkeying the eccentric 25 from its shaft 65 26, the weight of the parts serving to keep the cam in its lowest or working position, or a stop may be used to keep it there. When more than two sheets are to be collected by the carrier G before the folding off takes place, the relative speeds of rotation of the carrier G and of the cams N is varied accord- 70 ingly, and the adjunctive mechanism for operating the cam 22 is also operated at a suitable speed. Thus if four sheets are to be collected the cam 22 is operated to open the grippers on the carrier at every fourth set 75 that passes it or at every one and one-third revolution of the carrier. If five, seven, eight, or more sheets are to be collected, then the cam 22 is operated at every one and two-thirds, two and one-third, two and two-thirds, &c., revolutions of the carrier G. In order to avoid the protrusion of the blades 17 18 at any point other than at the one point where the folding-off occurs, it is preferable to arrange the driving mechanism for 80 one of the carrier and cam elements so that the cams N will lose or gain one-third of a turn on the carrier in the intervals between the successive foldings off. Gearing for this purpose is indicated in Fig. 2 by the pitch- 85 circles thereof.

In the modification illustrated in Figs. 8 and 9 the parts indicated by the references p q r r² x y z 5 12 13 16 17 18 19 20 21 22 28 29 30 are the same in construction and function 90 as the like parts shown in Figs. 2 and 3. The gears M and cams N are omitted, and the blades x y z are withdrawn inwardly of the cylinder G² by springs 81, which are secured at their ends to the bars carrying the blades and 100 to the arms 12, there being two springs for each blade. For the purpose of moving the blades outward to fold off the sheets and to allow of the collection of cuts or sheets I may employ rocking cams N², which are operated 105 by means of eccentrics 83 on the shaft 10 and eccentric-straps and links 84, there being a cam, eccentric, link, and strap at each end of the cylinders G² and H. The blades x y z contact with the cylinder H, as in the case previously described, and the other parts, as grippers 16 17 18, &c., have the same functions 110 in both cases. The described arrangement of the parts causes the collecting of two cuts, the cam 22 being moved to and fro in the 115 manner above set forth. When it is desired to fold cuts without collecting them, the cams N² are disconnected from the shaft 10 and are locked in their outer or working positions, as by pins 44^a, which pass through 120 suitable holes in the framework and engage with or behind the cams N², as indicated in dotted lines. In this case also more than two sheets may be collected by driving the 125 cylinders G² H as described, by having the eccentrics 83 loose on shaft 10, and by gearing them with cylinder G² in any suitable manner.

It will be observed that the sheets are fed to the cylinders G G² at a point closely adja- 130

cent to that where they are folded off these cylinders onto the cylinder H and that the feed is in a direction that cuts across the cylinders G G² or secantwise thereof. Also that with the cylinders G (or G²) and H running at the same surface speed as the printing-cylinders of the presses the sheets are fed to the folding-cylinders with their heads and tails touching, whence it results that the grippers of the cylinder G (or G²) push out the tails of the sheets in order to take the heads of the following sheets.

Other means for preventing the transfer of sheets except at stated intervals may be employed without departing from the broad principle of my invention. I do not, therefore, limit myself to the forms of my invention above described.

What I claim as new, and desire to secure by Letters Patent of the United States, is—

1. The combination of a rotating carrier provided with a plurality of non-rotating folding-blades, rotating cams for protruding said folding-blades, and mechanism for rotating said cams and said carrier in different times, substantially as described.

2. The combination of a rotating carrier, a non-rotating folding-blade movable radially thereof, a rotating cam, and connection between said cam and said blade having a part coacting with and revolving about the same axis as said cam but in a different time, substantially as described.

3. The combination of a rotating carrier, a plurality of folding-blades movable radially thereof, a rotating cam, and an independent connection between said cam and each of said blades having a part coacting with and revolving about the same axis as but at a rate of speed different from that of said cam, substantially as described.

4. The combination of a rotating carrier, an in-and-out movable non-rotating folding-blade thereon, and a cam revolving about the same axis as but independently of said carrier and at a different rate of speed and connected with said blade to control the protrusion of the same, substantially as described.

5. The combination of a rotating carrier, a plurality of in-and-out movable folding-blades thereon, and a cam revolving about the same axis as said carrier but at a different rate of speed and connected independently with said blades to control the protrusion thereof, substantially as described.

6. The combination of a rotating carrier provided with a plurality of folding-blades, and moving cams connected with said blades at each end of the carrier for causing the protrusion of said blades each during non-consecutive revolutions of the carrier, substantially as described.

7. The combination of a rotating carrier provided with a plurality of folding-blades, and rotating cams connected with said blades

at each end of the carrier for causing the protrusion of said blades each during non-consecutive revolutions of the carrier, substantially as described.

8. The combination of a rotating carrier provided with a plurality of folding-blades, and rotating cams having the same axis of rotation as said carrier and connected with said blades at each end of the carrier for causing the protrusion of said blades each during non-consecutive revolutions of the carrier, substantially as described.

9. The combination of a rotating carrier provided with a plurality of folding-blades, rotating cams connected with said blades at each end of the carrier, mechanism for rotating said cams in time different from that of the carrier, said mechanism having disconnectible parts, and means for locking said cams against motion while said mechanism is disconnected, substantially as described.

10. The combination of a rotating carrier provided with a plurality of folding-blades, rotating cams having the same axis of rotation as said carrier and connected with said blades at each end of the carrier, mechanism for rotating said cams in time different from that of the carrier, said mechanism having disconnectible parts, and means for locking said cams against motion while said mechanism is disconnected, substantially as described.

11. The combination of a rotating carrier provided with a plurality of reciprocating folding-blades, rotatory cams for protruding said blades, mechanism provided with disconnectible parts for rotating said cams and said cylinder in different times, and means for locking said cams against motion, substantially as described.

12. The combination of a rotating carrier provided with a plurality of folding-blades, movable cams for protruding said blades, and mechanism provided with disconnecting parts for operating said cams and for locking them against motion, substantially as described.

13. The combination of cylinder G, three non-rotative folding-blades mounted therein, cams N connected with said folding-blades, and mechanism for revolving said cylinder and said cams in different times, substantially as described.

14. The combination of an internal guide or V-shaped former, a pair of rolls at the apex thereof, and a collar on at least one of said rolls, said collar being of a diameter somewhat greater than the diameter of the corresponding roll and being adjustable longitudinally relatively to its said roll and coacting with a web-margin, substantially as described.

15. The combination of an internal guide or V-shaped former, a pair of rolls at the apex thereof, and collars on said rolls, said collars

being of diameters somewhat greater than the diameters of their respective rolls, and one collar per roll being adjustable longitudinally relatively to its roll, and said adjustable collars coacting with a web-margin, substantially as described.

16. The combination of an internal guide or V-shaped former, a pair of rolls at the apex thereof, and collars adjustable longitudinally of said rolls, each collar being of greater diameter than its own roll and said adjustable collars coacting with a web-margin, substantially as described.

17. The combination of a web-press whose two impression-cylinders rotate in opposite directions and perfect a web, a second web-press whose impression-cylinders all rotate in one direction, and a third (perfecting) web-press, with mechanism for driving the impression-cylinders of the third press in opposite directions or in the same direction, whereby two webs may be printed upon on both sides and one of them may receive multicolored impressions upon one side or may be perfected merely with but one color upon each side, substantially as described.

18. The combination of a web-press whose two impression-cylinders rotate in opposite directions and perfect a web, a second web-press whose impression-cylinders all rotate in one direction, and a third (perfecting) press, with mechanism for driving the impression-cylinders of the third press in opposite directions or in the same direction, said presses being one above another, a web-associator, and a folding-machine to which the associated webs are taken, whereby two webs may be printed upon on both sides and one of the webs may receive multicolored impressions upon one side or may be perfected merely with but one color on a side, substantially as described.

19. The combination of a web-press having its impression-cylinders geared together to rotate in opposite directions, a second web-press having a pair of impression-cylinders, disconnectible gearing for connecting said pair of impression-cylinders to cause them to rotate in opposite directions, and disconnectible gearing between a cylinder of the first press and the first impression-cylinder of the second press for driving the last-named cylinder in the same direction as the second impression cylinder of the second press, whereby each press may perfect its own web, or one web may be run through both presses and receive impressions on but one side in one of said presses, substantially as described.

20. The combination of the impression-cylinders i of press C, impression-cylinders i^2 of press D, gears 46 47 connecting the last-named cylinders, one of said gears being movable along or disengageable from its shaft, and gears 48 49 50 connecting the first impression-cylinder of press C with the first im-

pression-cylinder of press D, one of said gears 48 49 50 being movable along or disengageable from its shaft, substantially as described.

21. The combination of a pair of impression-cylinders arranged adjacent each other, disconnectible gearing between said cylinders for driving them in opposite directions, a second pair of impression-cylinders, said pairs of cylinders being arranged one over the other, form-cylinders coacting with said impression-cylinders, said pairs of impression-cylinders and their co-operating form-cylinders constituting two perfecting-presses, and disconnectible gearing between a cylinder of the press containing said second pair of impression-cylinders and the first impression-cylinder of the press containing said first-named pair of impression-cylinders, said last-named gearing being arranged for driving said first impression-cylinder in the same direction as its companion impression-cylinder, substantially as described.

22. The combination of a plurality of web-perfecting presses, a brake mechanism for and coacting with a cylinder of each press, a power-controller, a lever, and means for connecting said lever with said controller and with said brake mechanisms, whereby said brakes are applied and taken off as the power is taken off and put on, with driving mechanism for said presses, connecting by a single gear with the power-shaft, substantially as described.

23. The combination of a plurality of web-perfecting presses, a brake mechanism for and coacting with a cylinder of each press, a power-controller, rock-shaft 60, mechanism for connecting said controller and said brake mechanisms with said shaft to be operated simultaneously, means for actuating said shaft, and driving mechanism for said presses connecting by a single gear with the power-shaft, substantially as described.

24. The combination of a plurality of web-perfecting presses, a brake mechanism for and coacting with a cylinder of each press, a power-controller, rock-shaft 59, a lever on said shaft, mechanism for connecting said lever with said controller and with said brake mechanisms, and driving mechanism for said presses connecting by a single gear with the power-shaft, substantially as described.

25. The combination of a plurality of web-perfecting presses, a brake mechanism for and coacting with a cylinder of each press, a drive-shaft, a single gear on said shaft and connected with all of said presses to drive the same, tight and loose pulleys on said shaft, a slow-speed pulley on said shaft between said tight and loose pulleys, a belt-shifter, and connections whereby said brake mechanisms are operated simultaneously with the shifter as the latter moves the belt onto and off the loose pulley, substantially as described.

26. The combination of a plurality of web-

perfecting presses, a brake mechanism for and coacting with a cylinder of each press, a drive-shaft, a single gear on said shaft and connected with all of said presses to drive the same, tight and loose pulleys on said shaft, a slow-speed pulley on said shaft between said tight and loose pulleys, a belt-shifter, an operating-lever, and connections between said lever and said shifter and said brake mechanisms for operating the same, substantially as described.

27. The combination of a number of web-perfecting presses placed one above another, a brake mechanism for and coacting with a cylinder of each press, gearing connecting said presses with a common source of power, and means for simultaneously operating all said brake mechanisms as the power is thrown off, substantially as described.

28. The combination of a number of web-printing presses arranged one above another, a drive-shaft geared with all said presses, a brake mechanism for and coacting with a cylinder of each press, a power-controller, and means for simultaneously operating said controller and said brake mechanisms, substantially as described.

29. The combination of a plurality of rotary printing-presses provided each with a brake mechanism coacting with a cylinder thereof, a common driving power for said presses, a power-controller, and means for simultaneously actuating said controller and said brake mechanisms, substantially as described.

30. The combination of a rotating carrier provided with grippers, a cylinder receiving sheets folded from said carrier, and means for guiding the sheets to the carrier in a direction cutting across (secantwise) the same at a point adjacent the point where the sheets are folded off from the carrier, substantially as described.

31. The combination of a rotating carrier provided with folding-off devices, grippers on said carrier, means for feeding sheets to said grippers in a direction which cuts across the carrier or is secantwise thereof at a point adjacent that where the sheets are folded off, and a delivery-cylinder coacting with said carrier, substantially as described.

32. The combination of a transverse web-cutting device, a rotating carrier provided with grippers, and a sheet-guideway from said cutting device to said carrier directing the sheets to said carrier secantwise thereof and having a space or opening adjacent the cylinder into which the grippers push the tails of the sheets that may be on the carrier as the grippers open and seize the heads of the following sheets, substantially as described.

Signed at New York city, in the county of New York and State of New York, this 2d day of February, A. D. 1897.

WALTER SCOTT.
